UNITED STATES PATENT OFFICE.

MAURICE L. REID, OF SAN FRANCISCO, CALIFORNIA.

HOT-WATER BAG.

1,317,102.

Specification of Letters Patent. Patented Sept. 23, 1919.

Application filed May 7, 1918., Serial No. 233,023.

To all whom it may concern:

Be it known that I, MAURICE L. REID, a citizen of the United States, residing at San Francisco, in the county of San Francisco and State of California, have invented certain new and useful Improvements in Hot-Water Bags, of which the following is a specification.

The present invention relates broadly to 10 improvements in receptacles and to that specific type known to the trade as hot water bags, bottles, syringes or the like. Receptacles of this character are generally made of rubber and are very prone to spring leaks 15 sooner or later so that their utility is quite limited. This is mainly due to the manner in which they are made, that is, their inherent structural defects, in that they are not properly reinforced to withstand the 20 rough usage to which they are put, or to weaknesses produced by the effect of the heat from the contents, or to the disintegrating effect of the chemicals that may be embodied in the liquid introduced thereinto, 25 causing the receptacle to develop thin spots that give way in due course.

It is to overcome these disadvantages that my invention has as its objective and to this end I resort to the expedient of reinforcing the receptacle as a whole both in 30 regard to its seams and other points where the strains are greatest, resulting in considerable prolongation of the life of the article under the most trying requirements, for example, of hospital use.

These and such other objects as may hereinafter appear are attained by the novel construction, combination and arrangement of parts to be hereinafter specifically described 40 and claimed. Reference will now be had to the accompanying drawings forming a part of this specification, wherein:

Figure 1 is a fragmentary view of the upper portion of a bag constructed in accordance with this invention, parts being broken away and shown in section to clearly disclose the details of construction;

Figs. 2 and 3 are sectional views somewhat enlarged and taken about on the lines 45 2—2 and 3—3 of Fig. 1, respectively;

Fig. 4 is a fragmentary view of the lower end of the bag showing the reinforced supporting tab more clearly; and

Fig. 5 is an enlarged sectional view 55 through the neck portion of the bag.

Throughout the following detail descrip-

tion and on the several figures of the drawings, similar parts are referred to by like reference characters.

The material of the body portion of the 60 bag which forms the subject matter of this invention is preferably of pure rubber interlaid with special strong cotton cloth or the like so that the article as a whole is built somewhat on the same principle as an 65 automobile tire. In other words, it will be observed in Figs. 2 and 3 that the walls of the bag consist of an outer layer of rubber 1, an inner layer 2, and an interposed layer of fabric 3. The edges of the respective 70 walls are vulcanized together in the customary manner but these seams in my construction are doubly reinforced. In other words, interiorly of the body I provide a rubber reinforcing strip 4 extending 75 entirely about the vulcanized seam from one side of the neck to the other side. Exteriorly I employ a further reinforcement for this seam construction in the form of a rubber strip 5 carrying a fabric strip 6 adhered 80 thereto. These reinforcing strips are of course designed to make the weak seam portions of the bag construction especially 85 strong and the interposed fabric layer in the walls themselves prevents the bag from stretching out of shape and developing thin spots hereinbefore referred to, when filled with hot water and subjected to heavy pressure.

The neck portion of the bag is also 90 specially formed to reinforce this part of the bag which is most often subjected to considerable strain. At the neck the mouth of the bag is provided with the usual metallic thimble 7 corrugated to constitute threads to receive the stopper 8. This thimble is set and vulcanized in pure rubber and extending about the outer layer of rubber is a wire band 9 which presses the rubber into the grooves of the thimble and prevents any 95 likelihood of displacement of the latter. Finally, about this neck portion I apply a reinforcing strip of combined rubber and fabric, as indicated at 10, similar in fact to the reinforcing strip comprising the elements 5 and 6 above described.

The bag is provided with the usual funnel like entrance 11, and the finger loop 12 to which the loss preventing connection 13 is attached at one end and to the stopper 8 at the other end.

In addition to the foregoing, the upper

portion is provided with a further reinforcing layer of rubber as indicated at 14 adhered to the walls of the bag and passing beneath the outer reinforcing strip 5-6 for 5 the edges of the bag.

At the bottom the bag is provided with the usual hanging or supporting tab 15 with the eyelet 16, this tab being formed of fabric reinforced rubber as clearly indicated in 10 Fig. 4. It will be apparent from the foregoing that the bag made in accordance with this description and arrangement is as strong as it is possible to construct it to best meet the requirements of usage in hospitals 15 and other places.

Having thus described my invention, what I claim as new is:

A water bag receptacle of the class described comprising side walls composed of vulcanized outer and inner layers of rubber and an intermediate layer of fabric, the 20 walls at the seams being vulcanized together, and reinforcing means for said seams consisting of an inner strip of rubber having a fabric face connected thereto by adhesion 25 extending centrally therealong and narrower than the rubber strip, the fabric faced side being adhered to the seam of the bag so as to provide against contact between the contents of the bag and the fabric and an outer 30 and similarly formed reinforcing strip.

In testimony whereof I affix my signature.

MAURICE L. REID.
